UNITED STATES PATENT OFFICE.

CHARLES MILLER, OF LONG ISLAND CITY, AND MAX FEINSTEIN, OF CORONA, NEW YORK; SAID FEINSTEIN ASSIGNOR TO SAID MILLER.

THERAPEUTIC SHOE.

Application filed July 7, 1927. Serial No. 203,903.

This invention relates broadly to the shoe art and deals more specifically with a therapeutic shoe or slipper.

It is an object of this invention to provide 5 a shoe which will conform correctly to the contour of the tread surface of the foot of the wearer.

Further it is an object of this invention to provide a shoe which is provided with supports for special parts of the wearer's foot, and which is also provided with increased 10 space for other special portions of the wearer's foot.

It is a further object of this invention to 15 provide a shoe which insures proper circulation of the blood in the wearer's foot.

And it is a further object of this invention to provide a shoe which checks perspiration of the wearer's foot.

20 Finally it is an object of this invention generally to improve the structure of a shoe or slipper.

These and other objects of the invention will be apparent to those skilled in the art 25 from the following description taken in connection with the accompanying drawing in which:

Fig. 1 is a fragmentary longitudinal sectional view of a shoe embodying the invention.

30 Fig. 2 is a transverse section taken on the line 2-2 of Fig. 1.

Referring in detail to the drawing, 10 designates a shoe or slipper which may be of the well known welt, turn, stitchdown, or any 35 other type. For the purposes of this disclosure we have shown the invention applied to a welt shoe, but the same applies also to the other aforementioned types. The shoe 10 is seen to comprise an upper 11, provided 40 with the usual lining 12 and box toe 13. The upper of the shoe may be of any of the standard structures and the same forms no part of the present invention. An outersole 14 is 45 attached to the welt 15. An innersole 16 is joined to the upper and the filler material 17 is placed between the inner and outer sole in the well known manner.

We have found that in ladies' slippers and 50 shoes with the present styles the forward portion of the wearer's foot is crowded into a

too small space to permit normal and proper circulation of the blood to all parts of the foot. In order to remedy this defect, we provide the concavity E which is positioned at the portion of the shoe where the big toe of the wearer's foot normally lies. There is thus assured an increase in space for the toes of the wearer without increasing the width of the shoe. The curvature of this concavity extends sidewise and forward to the upper 60 of the shoe. To the rear this curvature is more gradual, rising finally to the crest A at the metatarsal arch.

In order to properly support the foot at the metatarsal arch, we provide the concavities B and C which together with the crest A form an arch support for the metatarsal joint, which support has a gradual and normal curvature to accommodate the contour of the wearer's foot. Not only is there 70 provided increased space for the wearer's foot in a shoe of a given size, but also the bottom of the shoe conforms to the contour of the wearer's foot, thus providing support for portions of the foot which are arched. Also, when the wearer's foot is in motion as in 75 walking or dancing, for example, the portion of the sole extending from the crest A to the concavity E contacts intimately with the wearer's foot and as the sole of the shoe bends this portion thereof performs a massaging 80 operation upon the foot, thus enhancing the circulation of the blood in the foot.

The curvature in the innersole may be obtained by molding the same prior to its incorporation in the shoe and subsequently filling the resulting curvature at the bottom to provide a uniform flat surface for contact with the outsole or alternatively the desired curvature may be had by forming the shoe on a last 90 such as is disclosed in our copending application, Serial No. 172,237, filed March 3, 1927.

Having thus described our invention we desire to claim and secure by Letters Patent of the United States:

1. A shoe having an innersole, said innersole being provided with a concavity extending longitudinally thereof from a point at the ball line to the toe portion thereof.
2. A shoe having an innersole, said inner-

sole being provided with a concavity extending forwardly longitudinally thereof from a point adjacent to the ball line and extending transversely of said innersole from one side 5 of the toe portion to the other side thereof.

3. A shoe having an innersole, said inner-sole being provided with a transversely con-

vex curve at the ball line, adapted to support the metatarsal arch of the foot of the wearer, and a concavity extending forwardly from 10 said curve to the toe portion of said inner-sole.

CHARLES MILLER.

MAX FEINSTEIN.
